United States Patent Office

Des. 188,062
Patented May 31, 1960

188,062

WATCH

Raymond Prétat, Porrentruy, Switzerland, assignor to Arthur Prétat & fils, S.a.r.l., Porrentruy, Switzerland, a Swiss company

Filed Dec. 29, 1958, Ser. No. 53,963

Claims priority, application Switzerland July 11, 1958

Term of patent 3½ years

(Cl. D42—8)

FIG. 1.

FIG. 2.

FIG. 3.

FIG. 4.

Fig. 1 is a bottom plan view of the design for a watch;

Fig. 2 is a side elevation view of the watch of Fig. 1; Fig. 3 is a top plan view of the watch of Fig. 1; and Fig. 4 is a bottom perspective view of the watch of Fig. 1 with the stem removed for clarity.

The essential features of my design reside in the parts shown in full line in the drawing.

I claim:

The ornamental design for a watch, as shown and described.
